UNITED STATES PATENT OFFICE.

ARTHUR BAYTON, OF MANILA, PHILIPPINE ISLANDS.

GOLD-SAVING DEVICE.

1,268,670.

Specification of Letters Patent.

Patented June 4, 1918.

Application filed September 26, 1917. Serial No. 193,332.

To all whom it may concern:

Be it known that I, ARTHUR BAYTON, a citizen of the United States, and a resident of Manila, Philippine Islands, have invented 5 a new and Improved Gold-Saving Device, of which the following is a full, clear, and exact description.

The prime object of my invention is to provide disintegrating means to be employed 10 in connection with sluice boxes, more particularly the sluice boxes of gold dredges and so arranged as to break up and reduce all clay and sticky gold-bearing material so that the same can be thoroughly washed and 15 be made to give up any gold that it contains before passing over the tail of the box. The stated object is attained by a disintegrating wheel disposed in the sluice box so as to be directly in the path of the material passing 20 through the box, in a manner to require that the material be broken up in order to pass the disintegrating wheel.

Other objects of the invention and the nature thereof as well as important appurte- 25 nances of the same and the advantages will clearly appear as the description proceeds.

Reference is to be had to the accompanying drawings forming a part of this specification in which similar reference characters 30 indicate corresponding parts in all the views, it being understood that the drawings are merely illustrative of one example of the invention.

Figure 1 is a longitudinal vertical section 35 of a portion of a sluice box equipped with my invention;

Fig. 2 is a transverse vertical section on the line 2—2, Fig. 1;

Fig. 3 is a sectional plan view given to 40 show one practical manner of arranging the knives and subordinate elements on the face of the wheel;

Fig. 4 is a perspective view of a detail to be hereinafter referred to.

It is to be understood that the invention 45 is applicable to any approved sluice box or the like, through which the gold-bearing material is sluiced. In the sluice box 10 I dispose a disintegrating wheel designated

50 generally by the numeral 11 and here shown as turning on a base plate 12, a wedge-shaped shim 13 being employed beneath the base plate to level the wheel. The base plate 12 is secured on the bottom of the sluice box 55 in any suitable manner as by bolts 12^a. The wheel 11 is mounted on an upright shaft 14

to which, in practice, said wheel is both keyed and shrunk, said shaft extending through a boss 15 in the base plate 12, the base having a gland 16.

Cast integral with the wheel, or otherwise produced in fixed relation thereto, are knives 17, there being advantageously two annular series of the knives and each knife tapering toward its forward edge and preferably having a rounded back surface 17^a struck from the center of the wheel. The numerals 18, 19 merely indicate the arbitrary surface formation of the disintegrating wheel which aside from the knives 17 will be given in practice 70 any suitable form to produce the desired strength with lightness. It is to be understood that the height of the knives 17 will vary with the geological formation from which the material is taken. The material 75 is delivered to the sluice box at the forward side of the wheel 11 by a drop chute 20, and the wheel extends the full width of the box so that the material received from the chute 20 in order to pass through the wheel must 80 be thoroughly broken up by the knives 17. The wheel it is to be observed, forms part of the sluice box surface at the bottom, and interrupts the regular continuity of the box only in presenting a revolving barrier in the 85 path of flow of the material, requiring the material to flow across the face of the wheel and through a field of revolving disintegrating elements perpendicular to the path of flow, and cutting said path and therefore 90 repeatedly cutting the material, by cutting movements in opposite directions across the flow as the material passes over the wheel from the near side, across the center, to the opposite side. Thus, any sticky matter will 95 be disintegrated and brought to a fluid form such as to be easily washed for saving any gold therein that would otherwise be lost.

The employment of my disintegrating wheel 100 may be made to do away with the screen now largely used on dredges, thereby giving more table space, or if the screen be used the wheel will do away with the high pressure water nozzles providing the wheel is placed ahead of the screen. Thus, a large saving is 105 made in the pump power used in the washing.

In order to protect the disintegrating wheel from being damaged by any large rocks or stones, I provide a series of bars 110 21 disposed longitudinally in the box at the wheel and above the same. The bars may

be employed in any suitable number and at a distance apart depending on the width of the sluice box and the capacity of the buckets delivering the material thereto. The bars 5 are supported in any suitable manner as for example at the lower ends on a cross bar 22, extending between the sides of the box and at the upper end in a bracket 23 shown best in Fig. 4, the bracket being forked to receive 10 the bar. The numeral 24 indicates side plates on the sluice adjacent to the wheel 11 and protective bars 21 to take the wear and protect the sides of the box.

It will be obvious that the wheel may be driven in any suitable manner, the means shown being found efficient for the purpose to drive the wheel at approximately 500 revolutions per minute. Thus, the lower end of the shaft 14 turns in a bracket 25 on one 20 of two hangers 26 and a bevel pinion 27 on the shaft meshes with the bevel gear wheel 28 on a drive shaft 29 turning in bearings 30 in the hangers 26 and driven in any suitable manner, there being shown pulleys 31 to 25 receive power from a belt 32 which may be driven from any convenient source of power (not shown).

I wish to state in conclusion that although the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

1. In an apparatus of the class described, 40 a sluice box, and a disintegrating wheel disposed in the box and extending across the same, forming part of the bottom surface thereof, over which the material may flow across the face of the wheel from one side to 45 the other.

2. In an apparatus of the class described,

Copies of this patent may be obtained for five cents

a disintegrating wheel, means to mount the same in a sluice box to range transversely across the same at the bottom and form part of the bottom surface, and disintegrating elements disposed about the upper face of the wheel and projecting upwardly therefrom perpendicularly to the flow of material passing through the sluice box to intercept and break up the material directed to the wheel. 55

3. The combination with a sluice box, of a disintegrating wheel turning approximately horizontally therein on the bottom thereof, means to drive said wheel, and spaced protective bars disposed above the wheel and extending from a point beyond the front thereof to the opposite side of the wheel to carry rocks past the latter to prevent damage to the wheel. 60
65

4. The combination with a sluice box, of a drop chute therein, a disintegrating wheel in the sluice box at the bottom and disposed across the same at the lower end of the said drop chute, means to drive the said disintegrating wheel, and spaced protective bars mounted in the sluice box longitudinally thereof above the said disintegrating wheel. 70

5. An apparatus of the class described, including a sluice box, and a disintegrating wheel mounted in the sluice box and extending transversely across the same at the bottom to constitute a portion of the bottom surface of the sluice and over which the material will be required to flow in passing said wheel, said wheel having disintegrating elements projecting from its upper surface perpendicular to the direction of the path of flow of the material passing through the sluice box, and means to revolve said wheel to cause the disintegrating elements to be moved in opposite directions across the flowing material as the latter passes over the surface of the wheel from one side thereof to the other. 75 80 85 90

ARTHUR BAYTON.
